UNITED STATES PATENT OFFICE.

HORACE J. CLARK, OF DENVER, COLORADO, ASSIGNOR, BY MESNE ASSIGNMENTS, TO ELLA U. CLARK, OF SAME PLACE, CLINTON D. BOUTON, OF ITHACA, NEW YORK, AND HENRY H. GREEN, OF SUNSHINE, COLORADO.

OXIDIZING-FURNACE.

SPECIFICATION forming part of Letters Patent No. 620,887, dated March 14, 1899.

Application filed March 12, 1898. Serial No. 673,654. (No model.)

To all whom it may concern:

Be it known that I, HORACE J. CLARK, a citizen of the United States, residing at Denver, in the county of Arapahoe, State of Colorado, have invented certain new and useful Improvements in Oxidizing-Furnaces, of which the following is a specification, reference being had therein to the accompanying drawings.

10 This invention relates to an oxidizing-furnace for the purpose of drying, roasting, and desulfurizing ores of various characters.

The invention has for its object to provide an improved construction of oxidizing-flue by 15 which the ore will be gradually fed from one end of the same to the other.

It has for a further object to provide means by which the ore may be oxidized either by radiated heat or by the direct application of 20 the products of combustion to the ore. Provision is also made by means of which the ore may be dried preparatory to the oxidizing operation.

Other objects and advantages secured by 25 reason of the improved details of construction will be set forth in the following specification and clearly defined by the appended claims.

In the drawings, Figure 1 is a vertical longitudinal section of the invention. Fig. 2 is a vertical cross-section on the line 2 2 of Fig. 1. Fig. 3 is an enlarged detail horizontal section of the oxidizing-flue and retarding-plates. Fig. 4 is a detail perspective of the 35 discharge connection for the oxidizing-flue, and Fig. 5 is an end elevation of a modified form of the oxidizing-flue.

Like letters of reference indicate like parts throughout the several figures of the drawings.

This invention consists, essentially, of an oscillating oxidizing-flue A, which may be suitably inclined, as shown in Fig. 1, and supported in any suitable manner—for instance, upon a horizontal beam A', from which extend at opposite sides arms A². These arms are provided at their ends with rollers A³, seated in suitable bearings A⁴, formed in the forked ends of the arms. The

oxidizing-flue is composed of a casing formed 50 in a series of sections a, which are lined with fire-brick a' or other suitable refractory material, the said casing A being composed of two parts joined together upon a horizontal line at opposite sides, as shown at a². The 55 abutting ends of the sections of casing a are provided with flanges a³, by means of which they may be joined together to form the complete flue and to support in position the refractory lining a'.

Any suitable means may be used for oscillating the flue; but I have illustrated in this application a segmental peripheral gear B, located upon the flue A and engaging with a segmental gear B', suitably supported adjacent to 65 said gear B. The gear B' is provided with an extending arm B², which is slotted and eccentrically connected by a bolt B³ with a rotating disk B⁴, mounted upon a support B⁵ and driven by any suitable power. The movement of the 70 arm B² imparted by the disk B⁴ causes the segmental gear B' to engage the gear B, and thus swing or oscillate the flue A. The opposite ends of the flue are provided, respectively, with any suitable form of fire-box and smoke-stack, instances of which are illustrated in Fig. 1, wherein a fire-box C is provided having an inner side wall C', between which and the outer wall an air-chamber is formed. The blast of air necessary to develop the desired 80 heat in the flue is introduced through the pipe C² into the air-space between the walls and becomes highly heated before it is admitted into the fire-box at the apertures C³ below the grate C⁴. The under surface of 85 the fire-box is provided with suitably-curved supports C⁵, which permit the tilting of the same at any desired angle to effect the inclination of the flue. The supporting-beam A' is rigidly bolted to the fire-box, as at a⁴, and 90 the flue A is connected to the fire-box by means of a flange c, which overlaps a flange a³, formed on one of the sections a of the flue-casing. An oscillation of the flue is thus permitted, while the flange prevents any longitudinal movement of the parts in relation to 95 each other.

The opposite end of the flue A is connected

to the smoke-box D' and smoke-stack D by a flange d, similar to the flange c, overlapping the flange a³ of one of the sections a. The smoke-stack is provided with a telescoping section D², within which the section D will move, and the smoke-box at its lower portion is formed with a bearing D³, to which the beam A' is secured by means of bolts a⁴, about which bearing the segmental gear I' is journaled. The bearing D³ is provided with a seat d', in which rests the pivotal point of an adjusting-screw D⁴, which screw at its lower end is suitably threaded into a base D⁵ and is provided with an operating-nut d². It will be obvious that an operation of this nut will adjust the end of the flue and the parts carried thereby in a vertical plane, as the fire-box will rock upon the curved support C⁵, and the desired inclination to the flue can thus be obtained for any particular character of work to be performed. The material to be fed to the oxidizing-flue may be introduced through the feed-chute E, passing through the smoke-box and having at its outer end a hopper E'. This chute is provided with any suitable form of conveyer—for instance, a screw conveyer E², driven by a pulley E³ at the outer end of the shaft E', upon which the conveyer is carried. The location of the feed-chute in the smoke-box serves to maintain the same in a heated condition, and thus remove from the material any slight moisture which may be contained therein.

For the purpose of adapting the oxidizing-flue for the treatment of ore by the closed-muffle or radiated-heat processes or when desired by the open-hearth the hereinafter-described construction of parts is provided. To accomplish these functions, the flue is divided into a series of independent passages, comprising a central passage F, having a passage F' above the same and a passage F² below. These passages are formed by horizontal plates f, of any suitable refractory material, held in relative position by the refractory lining-blocks f' at opposite sides. These passages may be provided with retarding-plates of any suitable construction—for instance, the plates G, shown as applied in the central passage F and which are held in position by lugs G', formed on the plates and seated in suitable apertures formed in the horizontal plates f. These plates are of suitable refractory material and extend alternately from opposite sides of the passage F, the ends thereof slightly overlapping, so as to prevent a direct channel at any time through the passage. The function of the plates is to retard the ore's passage through the flue, as in the oscillation of the flue the ore will be thrown to the lowest side of the same, and owing to the inclination of the flue will move forward into contact with the next succeeding plate. Upon the oscillation of the flue in the opposite direction the same action occurs, so that the ore is gradually fed downward from side to side and gradually

progressing, whereby the particles are stirred and agitated, so that the heat will act upon all surfaces thereof and the ore be retained in the passage of the flue for the proper predetermined length of time for effecting the desulfurizing or roasting of the ore. During such action the sulfur-fumes will be carried by the draft and discharged into the smoke-stack through the apertures e, provided in the feeding-chute E, which communicates with this central passage F.

After passing from the passage F the ore is conveyed through a discharge-pipe H, which passes through the fire-box and is secured to the flue A, as at H', so as to be carried thereby in the oscillation of the flue. This pipe at the end H' is formed rectangular in shape to conform to the configuration of the passage F and at its outer end H² is formed circular, so as to discharge into a down-chute I. The end H² of this pipe is covered by a cap I', which is closed, except a small aperture I². This closing-cap is used to prevent the contact of cold air with the ore in the passage, as the contact with such air would exert a cooling influence upon the liberated sulfur-fumes, causing the same to condense and fall back among the ore, thereby defeating the successful operation of the invention. The aperture I² is only of sufficient size to admit the necessary amount of air to accomplish the oxidizing operation. The pipe H is provided with an aperture h in its upper surface, which is closed by a movable cover h', operated by any suitable connection extending through the walls of the fire-box and is for a purpose to be hereinafter described.

Fig. 5 illustrates a detail of a modified form of the oxidizing-flue and also a form of plug or stopper J, several of which are provided and formed to close the end of any one or more of the passages in the flue at their junction with the fire-box. This figure also shows a form of ore-discharge K, located at one side of the flue A and communicating with the passage F. When this is used, the pipe H can be dispensed with and the ore discharged without passing through the fire-box. It is, however, preferable to pass the ore through the discharge-pipe H in the fire-box, as by this means the ore is subjected to the most intense heat at the proper time to effect the completion of the oxidizing operation and prevent the condensation of any of the sulfur-gases which may have been freed during the roasting operation. When the discharge K is used, the central plug or stopper J will be inserted, and either one or both of the segmental stoppers J' may be removed to permit the products of combustion to pass through the upper and lower passages in the flue.

In the usual process of desulfurizing ore the same is fed in a granulated or reduced condition into the hopper E' and fed by the conveyer into the inclined oscillating flue, the ore passing through the passage F and being thereby retarded in its feed, while the prod-

tics of combustion pass through the upper and lower passages F' and F^2 , so as to thoroughly heat the central passage F by radiation, and thereby accomplish the desulfurizing of the ore without the contact of the same with the products of combustion. The ore is most highly heated as it is discharged from the passage F and into the discharge-pipe H , passing through the fire-box. The speed of oscillation can be varied for timing the roasting operation to adapt the same for different classes of ore, and the same result can be obtained by an adjustment of the inclination of the flue. If the ore is to be discharged at the side of the flue, the plug J will be inserted in the end of the passage F , while the preceding steps of the operation will remain the same. In the event that it is desirable to permit the passage of the products of combustion directly into contact with the ore, as in the case of an open-hearth furnace, the door h' will be opened, permitting the entrance of the products of combustion into the passage F and also above and below the same. This same operation would be performed with a moderate degree of heat when it is desired to utilize the furnace as a drier for drying the ore preparatory to the roasting operation. In the treatment of certain classes of ore the drying operation may be performed simultaneously with the roasting or oxidizing operation, and to adapt the flue for this purpose a hopper L may be applied at the smoke-box end thereof, as indicated by dotted lines in Fig. 1. Under this condition a discharge-opening L' will be provided at the fire-box end of the passage F' and the plug J' used to close this passage. It may be stated, however, that it is unnecessary to completely close the end of this passage, and the proper operation may be performed by a plate of sufficient height to prevent the ore from rolling into the fire-box. When the flue is constructed in this manner, the ore to be dried will be fed into the passage F' through the hopper L and dried during its gradual movement therethrough, while the ore to be roasted will pass through the passage F . The necessary heat for the operation may be secured by the products of combustion passing through the flue F^2 and also, if desired, through the passage F' .

The invention has been particularly described and is intended primarily for the roasting and treatment by heat of ores; but it is obvious that the same may be adapted for roasting or drying other materials and that by the arrangement of flues hereinbefore described the products of combustion may be passed through any one of the passages illustrated or excluded from any of the same, as may be found desirable in different classes of work. The invention is not limited to a flue having three passages, as illustrated, but any desired number may be provided which may be found desirable in constructing the furnace. It is also obvious that numerous

changes may be made in the details of construction of the several parts without departing from the spirit of the invention as defined by the appended claims. 70

Having described my invention, what I claim as new, and desire to secure by Letters Patent, is—

1. In an oxidizing-furnace, an inclined oxidizing-flue, means for oscillating the same transversely, and devices extending transversely of and partially across said flue to retard the passage of material therethrough; substantially as specified. 75 80

2. In an oxidizing-furnace, an inclined oxidizing-flue, means for oscillating the same, and retarding devices extending transversely from opposite sides and partially across said flue; substantially as specified. 85

3. In an oxidizing-furnace, an inclined oxidizing-flue, means for oscillating the same, and retarding-plates extending alternately from opposite sides of said flue; substantially as specified. 90

4. In an oxidizing-furnace, the combination with a furnace, of a stack, an oxidizing-flue extending between said furnace and stack, retarding devices extending alternately from opposite sides of said flue and means for oscillating said flue; substantially as specified. 95

5. In an oxidizing-furnace, the combination with a furnace, of a stack, an oxidizing-flue extending between said furnace and stack, retarding devices extending alternately from opposite sides of said flue, means for oscillating said flue, and means for supporting said flue in an inclined position; substantially as specified.

6. In an oxidizing-furnace, the combination 105
with a furnace, of a stack, an oxidizing-flue
extending between said furnace and stack,
retarding devices extending alternately from
opposite sides of said flue, means for oscillat-
ing said flue, and means for vertically adjust-
ing one end of said flue; substantially as speci-
fied. 110

7. In an oxidizing-furnace, a flue provided with transverse longitudinal partitions to divide the same into independent passages, and retarding devices extending transversely from opposite sides and partially across said flue; substantially as specified. 115

8. In an oxidizing-furnace, a flue provided with transverse longitudinal partitions to divide the same into independent passages, one of said passages being provided with retarding-plates extending alternately from opposite sides thereof; substantially as specified. 120

9. In an oxidizing-furnace, a flue provided 125
with transverse longitudinal partitions to di-
vide the same into independent passages, one
of said passages being provided with retard-
ing-plates extending alternately from oppo-
site sides thereof; substantially as specified. 130

10. In an oxidizing-furnace, the combination with a furnace, of an oxidizing-flue, and retarding devices extending transversely from opposite sides and partially across said

- 4
- flue, means for supporting said flue, and means for oscillating said flue; substantially as specified.
11. In an oxidizing-furnace, the combination with a furnace, of an oxidizing-flue, and retarding devices extending transversely from opposite sides and partially across said flue, means for supporting said flue, a peripheral gear provided upon said flue, and means for engaging said gear to oscillate the flue; substantially as specified.
12. In an oxidizing-furnace, the combination with a furnace, of an oxidizing-flue, and retarding devices extending transversely from opposite sides and partially across said flue, means for supporting said flue, means for oscillating said flue, and a feed device for introducing material into said flue; substantially as specified.
13. In an oxidizing-furnace, the combination with a fire-box, of a flue connected thereto, an ore-passage extending from said flue and through said fire-box, and retarding devices extending from opposite sides and partially across said flue; substantially as specified.
14. In an oxidizing-furnace, the combination with a fire-box, of a flue connected thereto, an ore-passage extending from said flue and through said fire-box, and retarding devices extending from opposite sides and partially across said flue, and means for oscillating said flue and ore-passage; substantially as specified.
15. In an oxidizing-furnace, the combination with a fire-box, of a flue connected thereto, an ore-passage extending from said flue and through said fire-box, means for oscillating said flue and ore-passage, and an aperture and closure for admitting the products of combustion to said ore-passage; substantially as specified.
16. In an oxidizing-furnace, the combination with an oxidizing-flue and means for oscillating the same, of retarding devices extending transversely from opposite sides and partially across said flue, a fire-box provided with air-inlets below the grate thereof, and means for supplying a forced draft to said air-inlets; substantially as specified.
17. In an oxidizing-furnace, the combination with an oxidizing-flue and means for oscillating the same, of retarding devices extending transversely from opposite sides and partially across said flue, a double-walled fire-box provided with an air-inlet below the grate, and means for introducing air into the space between said walls; substantially as specified.
18. In an oxidizing-furnace, the combination with an oxidizing-flue and means for oscillating the same, of retarding devices extending transversely from opposite sides and partially across said flue, a double-walled fire-box provided with an air-inlet below the grate, and an air-inlet located at the upper portion of said fire-box between said walls; substantially as specified.
19. In an oxidizing-furnace, the combination with an oxidizing-flue composed of a series of passages, of a fire-box adjacent thereto, and removable plugs adapted to close one or more of said passages at the end thereof adjacent to the fire-box; substantially as specified.
20. In an oxidizing-furnace, the combination with an oxidizing-flue, means for oscillating the same, and retarding devices extending transversely from opposite sides and partially across said flue, of a fire-box and smoke-box at opposite ends thereof, a supporting-beam connected to said fire and smoke boxes, and means upon said beam for supporting said flue; substantially as specified.
21. In an oxidizing-furnace, the combination with an oxidizing-flue, means for oscillating the same, and retarding devices extending transversely from opposite sides and partially across said flue, of a fire-box and smoke-box at opposite ends thereof, a supporting-beam connected to said fire and smoke boxes, means upon said beam for supporting said flue, and rotatable bearings for said flue; substantially as specified.
22. In an oxidizing-furnace, the combination with an oxidizing-flue, means for oscillating the same, and retarding devices extending transversely from opposite sides and partially across said flue, of a fire-box and smoke-box at opposite ends thereof, a supporting-beam connected to said fire and smoke boxes, lateral supporting-arms carried by said beam, and rotatable bearings at the ends of said arms; substantially as specified.
23. In an oxidizing-furnace, an oxidizing-flue provided with an ore-roasting passage and with an ore-drying passage, means for introducing and removing ore from said drying-passage and independent feeding and delivery devices for said ore-roasting passage; substantially as specified.
24. In an oxidizing-furnace, the combination with an oxidizing-flue, of a smoke-box provided at its under surface with a bearing, means for oscillating said flue independently of the smoke-box, and retarding devices extending transversely from opposite sides and partially across said flue and means for vertically adjusting said smoke-box; substantially as specified.
25. In an oxidizing-furnace, the combination with an oxidizing-flue, of a smoke-box provided at its under surface with a bearing, means for oscillating said flue independently of the smoke-box, and retarding devices extending transversely from opposite sides and partially across said flue and a screw for vertically adjusting said smoke-box; substantially as specified.
26. In an oxidizing-furnace, the combination with an oxidizing-flue, of a smoke-box provided with a feeding-chute extending

therethrough, means for oscillating said flue independently of the smoke-box, and retarding devices extending transversely from opposite sides and partially across said flue; substantially as specified.

27. In an oxidizing-furnace, the combination with an oxidizing-flue, of a smoke-box provided with a feeding-chute extending therethrough, means for oscillating said flue independently of the smoke-box, and retarding devices extending transversely from opposite sides and partially across said flue and a conveyer located within said chute; substantially as specified.

28. In an oxidizing-furnace, the combination with an oxidizing-flue, of a smoke-box provided with a smoke-stack carried thereby, means for oscillating said flue independently of the smoke-box, an adjusting device beneath said box to vertically adjust the same and a telescoping section for said smoke-stack; substantially as specified.

29. In an oxidizing-furnace, the combination with an oscillating oxidizing-flue provided with retarding devices extending transversely from opposite sides and partially across the same, of a peripheral gear provided thereon, a segmental gear meshing therewith, and means for partially rotating said seg-

30. mental gear in opposite directions; substantially as specified.

30. In an oxidizing-furnace, the combination with an oxidizing-flue provided with retarding devices extending transversely from opposite sides and partially across the same, of a fire-box, a discharge-pipe carried by said flue and extending through said fire-box; substantially as specified.

31. In an oxidizing-furnace, the combination with an oxidizing-flue provided with re-

tarding devices extending transversely from opposite sides and means for operating the same, of a fire-box, a discharge-pipe carried by said flue and extending through said fire-box, and a stationary cap provided with an air-inlet and surrounding the outer end of said flue to discharge material into a chute; substantially as specified.

32. In an oxidizing-furnace, the combination with an oxidizing-flue, of a fire-box, a discharge-pipe extending through the same and provided with an opening communicating with the fire-box, and means for closing said opening; substantially as specified.

33. In an oxidizing-furnace, an oxidizing-flue provided with horizontal partitions, and retarding-plates provided with projections adapted to seat in said partitions; substantially as specified.

34. In an oxidizing-furnace, an oxidizing-flue provided with a refractory lining, horizontal partitions extending across said flue and retarding-plates cut away at their upper portions and extending from opposite sides of said flue; substantially as specified.

35. In a longitudinally oxidizing-furnace, an inclined quadrilateral oxidizing-flue and means for oscillating the same transversely; substantially as specified.

36. In a longitudinally oxidizing-furnace, an inclined quadrilateral oxidizing-flue, the opposite walls of which are parallel, and means for oscillating the same transversely; substantially as specified.

In testimony whereof I affix my signature in presence of two witnesses.

HORACE J. CLARK.
